ARTIFICIAL BAIT

Adolph R. Schueller, Minneapolis, Minn.

Application April 6, 1942, Serial No. 437,767

5 Claims. (Cl. 43—46)

My invention relates to artificial bait.

While the present embodiment of the invention is designed to simulate a minnow, it is equally well adapted for a design to simulate a crab or the like.

One of the objects of the invention is to provide a simulating body and a gang of co-operating hooks, wherein the major portions of the hooks are normally concealed in the body and with the pointed portions thereof so positioned relative to the body as to make the same inconspicuous.

Another object of the invention is to provide a simulating body and a gang of co-operating hooks, wherein the shanks of the hooks are normally removable and loosely held in a passageway in the body and in which at least one of the hooks holds the body from turning about the shanks and thereby holds the other hooks in predetermined relation to the body.

Still another object of the invention is to provide a simulating body having an upright passageway and a gang of cooperating hooks, the shanks of which extend loosely and removably into the passageway from the lower end thereof and wherein said body normally rests on the hook with freedom for movement outwardly of the shanks and onto a line attached to said shanks.

A further object of the invention is to provide a simulating body having an upright passageway and a gang of co-operating hooks, the shanks of which extend loosely and removably into the passageway from the lower end thereof and wherein the body is held by one of the hooks from rotating about the axis of the shanks, with the body extending between the pointed end portions of two of the hooks with pointed end portions of the hooks spaced outwardly from the sides of the body.

Another object of the invention is to provide a body simulating a minnow having a bendable tail of sufficient rigidity to stay where positioned.

Still another object of the invention is to provide a simulating body having a hook attached thereto for substantially relative universal movement and normally releasably held against movement relative to the body.

Other objects of the invention will be apparent from the following description, reference being had to the accompanying drawing.

To the above end, generally stated, the invention consists of the novel devices and combination of devices hereinafter described and defined in the claims.

In the accompanying drawing, which illustrates the invention, like characters indicate like parts throughout the several views.

Referring to the drawing:

5 Fig. 1 is a side elevation of the invention, some parts being shown in different positions by means of broken lines;

Fig. 2 is a plan view of the same;

10 Fig. 3 is a view partly in longitudinal central section and partly in side elevation; and

Fig. 4 is a view partly in transverse vertical section and partly in front elevation.

The numeral 5 indicates a buoyant body simulating a minnow, the tail of which, as shown, 15 is a vertically disposed thin piece or sheet 6 of bendable metal that will stay in the position in which it is bent laterally to cause the minnow to move on curves either by hand jerks on the line or the action of the waves when "still" fishing. This metal sheet 6 is covered on each side by a feather 7 and the feathers 7 are connected to each other and the metal sheet 6 by varnish or otherwise. The tail of the minnow is secured to the body 5 by cutting a scarf in the tail 20 end portion of the minnow and fitting said tail therein and securing the same by small rivets 8. The perimeter of the feathers 7 is trimmed to the shape of a minnow's tail.

Front and rear pairs of horizontally disposed 25 fins 9 and 10 cut from pieces of thin sheet metal are secured to the body 5 and extend outwardly of the sides thereof. The rear pair of fins 10 are at an elevation slightly above the front pair of fins 9 and the area of said rear fins is somewhat less than that of the front pair of fins 9.

An eye 11 is secured to the body 5 at the nose end thereof and projects forwardly therefrom. A trolling line 12, indicated by broken lines in Figs. 1 and 2, is attached at one end to the eye 11.

40 A pair of trolling hooks 13 is detachably secured to the body 5 either at the back thereof as shown by full lines in Figs. 1 and 2, or the under side thereof, as shown by broken lines in Fig. 1. The shanks 14 of the hooks 13 are sub-

45 stantially parallel and in close relation, the one to the other. These shanks 14 are connected at their outer ends and separated to form an eye 15. As one means of securing the trolling hooks 13 to the body 5, I provide two eye attachments 16

50 and 17 anchored to said body between the front and rear pairs of fins 9 and 10. The eye attachment 16 projects upwardly from the back of the body 5 and the eye attachment 17 depends from the under side of said body. To remove the 55 trolling hooks 13 from the eye attachment to

which they are secured, it is only necessary to force the respective eye attachment into the opening in the eye 15 to spread the shanks 14 apart and thread one of said shanks and the respective hook 13 through the eye attachment. To releasably hold the trolling hooks 13 against movement relative to the body 5, I provide for each eye attachment a pin 18 anchored to said body. Each of these pins 18 is adapted to be inserted between the shanks 14, slightly spread the same apart and thereby cause said shanks to pinch the respective pin 18 and thereby yieldingly hold said shanks 14 and hence the hooks 13. See Fig. 2.

Formed in the body 5 at the head end thereof and just forward of the front pair of fins 9 is a central upright passageway 19. A cavity 20 is formed in the under side of the body 5 rearwardly of the passageway 19. A gang of three hooks 21 for "still" fishing are circumferentially spaced equal distances apart about a common center. The shanks 22 of the hooks 21 are clustered and rigidly connected at their outer end portions by a sleeve 23 of solder or any other suitable means. Two of the shanks 22 are connected, extend outwardly of the sleeve 23 and spread apart to afford an eye 24. Obviously, the sleeve 23 and encased shanks 22 in a broad sense afford a single or common shank 25 for the hooks 21. The shank 25 normally extends into the passageway 19 from the under side of the body 5 with said body loosely resting on the downwardly and outwardly inner portions of hooks 21 and with one of the hooks 21 extending into the cavity 20. Obviously, the hook 21 in the cavity 20 holds the body 5 from turning about the projected axis of the shank 25. With one of the hooks 21 in the cavity 20, the body 5 extends midway between the other two hooks 21 which are held spaced outwardly from the sides of said body with their points materially above the under side of the body 5. As the inner portions of the hooks 21 and the shanks 22 are substantially entirely concealed in the passageway 19 with only enough of the pointed end portions of said two hooks projecting outwardly of the body 5 to hook and catch a fish, they are inconspicuous. One end of a line 26 is attached to the eye which, as shown, is above the body 5.

When trolling, a fish will strike the bait from the tail end and grab the hooks 13, but when "still" fishing, a fish will strike the bait from the under side and grab the two exposed hooks 21. As soon as a fish is caught on the hooks 21 and starts whipping action, in an attempt to free itself from the hooks, the body 5 will be forced outward of the shank 25 and onto the line 26 away from the caught fish. If the bait remained in its normal position relative to the hooks 21, said hooks would be bent and ruined by the caught fish.

If the improved bait is to be used for trolling, it is an extremely simple matter to remove the gang of hooks 21 and the attached line 26 from the body 5 and attach the trolling line 12 and the pair of trolling hooks 13 to said body, either above or below the same as indicated by full and broken lines, respectively, in Fig. 1. On the other hand, if the bait is to be used for "still" fishing, it is also a simple and easy matter to

remove the trolling line 12 and the trolling hooks 13 from the body 5 and insert the shank of the hooks 21 upwardly through the passageway 19 and attach the line 26 thereto.

The body 5 has indicated thereon oblique intersecting lines 27 that simulate the scales on a fish.

The drawing illustrates a commercial form of the invention, but it will be understood that the same is capable of certain modifications as to details of construction, arrangement and combination of parts within the scope of the invention herein disclosed.

What I claim is:

1. An artificial bait comprising a body having therein an upright passageway and also having a cavity in its under side, three hooks having a common shank loosely extending upwardly into the passageway from the under side of the body, and a line attached to the shank at its upper end, one of the hooks normally extending into the cavity and holding the body from turning about the longitudinal axis of the shank, the free end portions of the other two hooks being spaced outwardly of the sides of the body with the points of said two hooks above the under side of the body.

2. An artificial bait comprising a body having therein an upright passageway, a hook having a shank loosely and removably extending upwardly into the passageway from the under side of the body, and a line attached to the shank at its upper end, said shank and line being free for running movement through said passageway whereby the hook may be carried away from the body.

3. An artificial bait comprising a body having therein an upright passageway, a hook having a shank loosely and removably extending upwardly into the passageway from the under side of the body, a line attached to the shank at its upper end, said shank and line being free for running movement through said passageway whereby the hook may be carried away from the body, and means normally releasably supporting the body relative to the hook for direct lifting movement by the line.

4. An artificial bait comprising a body having therein an upright passageway, a plurality of hooks having a common shank loosely and removably extending upwardly into the passageway from the under side of the body, and a line attached to the shank at its upper end, said shank normally releasably supporting the body for direct lifting movement by the line and holding the same from turning about the longitudinal axis of the shank, said shank and line being free for turning movement through said passageway whereby the hook may be carried away from the body.

5. An artificial bait comprising a body having therein an upright passageway, a hook at the under side of the body, a line attached to the hook for free running movement through the passageway whereby the hook is free to be carried away from the body, and means releasably supporting the body relative to the hook for direct lifting movement by the line.

ADOLPH R. SCHUELLER.
